WALL LAMP

Quindora Jan McCuiston, 16016 N. 70th Drive,
Peoria, Ariz. 85345

Filed Apr. 16, 1975, Ser. No. 568,790

Term of patent 14 years

Int. Cl. D26—05

U.S. Cl. D48—4 B

FIG. 1 is a front perspective view of a wall lamp showing my new design, a portion of the shade being broken away for purposes of disclosure;

FIG. 2 is a fragmentary side elevational view of the lamp, the lamp being fragmentarily shown for convenience of illustration; and

FIG. 3 is a rear perspective view of the wall lamp of the present invention on a reduced scale.

I claim:

The ornamental design for a wall lamp, as shown and described.
